SHOE TREE

John W. Loney, Brockton, Mass., assignor to
 United Shoe Machinery Corporation, Borough
 of Flemington, N. J., a corporation of New
 Jersey

Application March 22, 1939, Serial No. 263,375

8 Claims. (Cl. 12—128.2)

This invention relates to expandible shoe trees intended to be placed in shoes when not in use for preserving their original appearance and shape. The sale of shoe trees having rigid shoe 5 engaging sections made of metal or wood is very much limited by the fact that, in order to fit all sizes of shoes, a retailer is required to carry a stock of a considerable number of sizes and this he is not always willing to do. Shoe trees have been provided, therefore, which have expandible foreparts and extensible heel parts, so that the tree will more readily fill the shoes of different shapes and sizes, both transversely and lengthwise of the shoe. To be satisfactory, such 10 a tree must be arranged so that the forepart sections may readily assume the positions which they are to occupy in any particular shoe without binding and this has not been found in prior shoe trees, because of the tendency of the coiled expansion springs commonly employed to catch upon the recesses provided to receive them in the forepart sections, or to catch upon the screw which sometimes has been employed as a combined limiting means and spring support for said 15 expandible forepart sections.

If a tree with an expanded forepart is provided with springs strong enough to cause the tree to firmly fill the shoe, then the user may encounter difficulty in inserting the forepart of the tree into the shoe. To obviate this difficulty, a cam is sometimes used for positively collapsing the forepart and holding it in collapsed position as the tree is inserted. One form of operating member for such a cam is connected to the heel part of 20 the tree, so that the tilting upward of the heel part, as would naturally be done in inserting the tree in the shoe, operates the cam to collapse the forepart.

It is an object of this invention to provide a simple, efficient and economical shoe tree having an expandible forepart and an extensible rear section whereby one tree may be used in shoes of different sizes and shapes.

In accordance with this object, a feature of 25 the invention resides in improved mechanism for controlling the expansion of the forepart sections and in which a member for limiting the expansion of such sections is combined with an arrangement facilitating the free action of the expanding springs employed. This, as illustrated, 30 comprises a plate adapted to be received in recesses in adjacent faces of the forepart sections, the plate being slotted to cooperate with pins in said sections to limit the expanding movement 35 and having tubular end portions which enclose

the mid-portions of spaced coil springs which coact with the forepart sections at points spaced longitudinally thereof.

Another feature will be recognized in an improved cam arrangement for collapsing the forepart sections when it is desired to insert the tree into a shoe.

This cam, positioned between the rearmost spring and the heel end of the forepart, operates to draw the forepart sections together and, in 10 its illustrated form, consists of a tubular cam which is received in recesses in the adjacent faces of the forepart sections and has two pairs of slots cooperating with a pair of pins in said sections. A connection to the heel part, comprising a flat plate positioned in a vertical plane to avoid interference with the forepart sections, is utilized as a cam operating member.

With the above and other objects in view, the invention will be described with reference to the 20 accompanying drawing and will be pointed out in the appended claims.

In the drawing,

Fig. 1 is a plan view, partly in section, showing the relationship of the parts when the tree is 25 fully extended;

Fig. 2 is a fragmentary perspective view illustrating the cam and showing the connection between it and one of the sections of the forepart, and

Fig. 3 is a side elevation showing the relative positions assumed by the forepart and the heel portion of the tree when the sections of the forepart are drawn together preparatory to inserting them into a shoe.

Referring to the drawing, the tree comprises a forepart divided into two sections 10, 12 (Fig. 1). These sections are urged apart to extend the shoe laterally by a pair of springs 14, 16 which are seated in recesses 18, 20 in the section 10, and 22, 24 in the section 12. The spreading of the sections 10, 12 is limited by a plate 26 which is seated in a saw kerf or slot 28 formed in the sections 10, 12. The plate 26 is loosely connected to the sections by pin-and-slot connections consisting of pins 30, 32 in the sections 10, 12 which pass through elongated slots 34, 36 in the plate 26. It is to be noted that the slots 34, 36 are somewhat wider than the diameter of the pins 30, 32 to permit a limited angular movement of the sections relative to each other so that they may adapt themselves to the shapes of different shoes. The ends of the plate 26 are formed into tubular portions 38, 40 which enclose the portion of the springs 14, 16 that would nor-

mally be exposed between the sections 10, 12 and extend into the spring receiving recesses 18, 20, 22, 24 so as to prevent the turns of the springs 14, 16 from binding on the edges of the recesses 5 and thus allow the sections to move freely relatively to one another and without any catching of the springs. The tubular portions 38, 40 are made slightly larger than the diameter of the springs 14, 16 so that the springs may move 10 freely in the tubular portions. Also, the tubular portions are somewhat smaller than the diameter of the recesses 18, 20, 22 and 24 so as to allow for free relative movement between the sections and the plate 26.

15 When the tree is prepared for insertion into a shoe the sections 10, 12 are drawn together against the action of the springs 14, 16 by a tubular cam member 42 which is located rearwardly of the tree from the springs 14, 16 and the plate 20 26 and has its end portions seated in alined recesses 44, 46 in the adjoining faces of the sections 10, 12. As is best shown in Fig. 2, the cam 42 has a set of cam slots 48, 50 formed at each end thereof, each set of cam slots consisting of an 25 upper and lower cam slot (Fig. 2) which is disposed within one of the recesses 44, 46. Passing through the cam slots 48, 50 are pins 52, 54 which are mounted in the sections 10, 12.

30 The cam 42 is rotated to draw the sections 10, 12 together by a bar 56 which is connected at one end to the mid-portion of the cam 42 and at the other end to the heel piece 68 of the tree. When this bar is moved in a height-wise direction with respect to the forepart to the position 35 shown in Fig. 3, the cam 42 is rotated so that the pins 52, 54 are moved into the parallel sections 58, 60 of the cam slots 48, 50 thus causing the sections 10, 12 to be moved together and held while the forepart is being inserted into a 40 shoe. After the forepart has been inserted into a shoe, the bar 56 and heel piece 68 are moved downwardly to bring a wide portion 62, 64 of the cam slots 48, 50 into register with the pins 52, 54 so that the sections of the forepart may be 45 pressed apart by springs 14, 16 to fill the shoe in which the tree is placed. It is to be noted that the wide portions 62, 64 of the cam slots extend outwardly beyond the pins 52, 54 so that they do not act to limit the outward movement of 50 the sections 10, 12 under the urging of the springs 14, 16, this being the function of the pins 30, 32. With this arrangement the pins 52, 54 will not act as a limiting means to the relative angular movement of the sections 10, 55 12.

The rearwardly extending portion of the bar 56 is slidably received in a recess 66 in the heel piece 68 and its withdrawal from this recess is prevented by a struck-out finger 70 which engages a plate 72 in the heel piece 68. The heel piece 68 is urged rearwardly away from the forepart by a spring 74 which is interposed between the end of the bar 56 and a wall of the recess 66 thereby to fill the shoe and extend it 65 lengthwise.

Having thus described my invention, what I claim as new and desire to secure by Letters Patent of the United States is:

70 1. A shoe tree comprising a forepart composed of laterally movable sections, a spring acting to move said sections apart, a plate loosely connected to said sections and arranged to limit the spreading movement of said sections, a cam arranged to draw said sections together, a heel 75 piece, and a connecting member joined to said

cam at one end and adjustably connected to said heel piece at the other, said heel piece being movable in a heightwise direction with the connecting member to rotate the cam and draw said forepart sections together. 5

2. A shoe tree comprising a forepart composed of laterally movable sections, a spring interposed between said sections and seated in alined recesses in said sections for urging the sections apart, a plate loosely connected to said sections and arranged to limit their spreading movement, a cam member located rearwardly of the spring and plate and seated in alined recesses in said sections, a plate connected at one end to said cam between the forepart sections, a heel piece having a recess therein in which the opposite end of the plate is slidably received, and a spring interposed between the plate and a portion of the heel piece for urging the heel piece away from the forepart. 10 15 20

3. A shoe tree comprising a forepart composed of laterally movable sections, a pair of spaced springs seated in alined recesses in said sections and acting to move the sections apart, a plate having tubular portions formed at its 25 opposite ends for enclosing said springs, said plate being loosely connected to said sections and arranged to limit their spreading movement, a cam located rearwardly of said springs operatively connected to said sections to draw them 30 together against the action of the springs, a cam operating member connected at one end to the cam and arranged to cause the cam to draw the forepart sections together when swung in a heightwise direction with respect to the forepart, a heel piece having a recess therein in which the opposite end of the cam operating member is slidably received, and a spring interposed between said cam operating member and the heel piece for urging the heel piece away 40 from the forepart. 35

4. A shoe tree having a heel part and a forepart divided longitudinally in sections, means for loosely connecting said sections comprising a slotted plate the front and rear ends of which 45 are provided with tubular portions which are received in recesses in the adjacent faces of the forepart sections, springs for expanding said sections positioned in said tubular portions, a tubular cam between said plate and the rear end 50 of the forepart sections received in recesses in the adjacent faces thereof and cooperating with said sections to collapse the forepart, and a vertical plate between said heel part and said cam arranged to rotate the cam upon heightwise 55 movement of the heel part.

5. A shoe tree comprising a forepart composed of laterally movable sections, a spring interposed between the sections of said forepart acting to move said sections apart, a plate having a portion thereof enclosing the section of the spring exposed between the sections of the forepart, said plate being connected to the sections of the forepart by pin-and-slot connections thereby to limit the spreading movement of the forepart sections under the urging of the spring, a tubular cam member located rearwardly of the spring and plate and having its end portions received in recesses in the forepart sections, cam tracks formed on the portions of the tubular 70 member in the recesses, pins in said forepart sections engaging said cam tracks, a cam operating member connected at one end to the tubular cam member and arranged to cause the cam to draw the sections together when swung in 75

a heightwise direction with respect to the forepart, a heel portion having a longitudinal opening therein in which the opposite end of the cam operating member is slidably received, and 5 a spring interposed between the cam operating member and a portion of the heel piece for urging said heel piece away from the forepart. 6. A shoe tree comprising a forepart composed of laterally movable sections, a pair of spaced 10 springs seated in alined recesses in said sections and acting to move the sections apart, a plate connected to each of said sections at spaced points by lost motion connections constructed and arranged to limit the spreading movement 15 of the forepart sections while permitting the sections to assume different angular positions relatively to each other, said plate having spaced tubular portions formed thereon arranged to enclose said springs and extend into the spring receiving recesses in the forepart sections, the tubular portions being smaller than the spring receiving recesses to permit a limited angular movement between the plate and the forepart sections, a cam member for drawing said sections together located rearwardly of the springs and plate and seated in alined recesses in the forepart section, a cam engaging member in 20 each of said sections arranged in cooperative relation with the portion of the cam member seated in the recesses of the sections, a heel piece, 25 and a connecting member joined at one end to 30

the cam member and at the other to the heel piece.

7. A shoe tree comprising a divided forepart composed of laterally movable sections having spring receiving recesses in the adjacent faces 5 thereof, a heel part, means for expanding said forepart comprising a coiled spring located in the recesses in adjacent faces of the forepart sections, and means for limiting said expanding movement including a tubular member enclosing the mid-portion of said spring and extending into the recesses in the forepart sections thereby to prevent the turns of the spring from binding on the edges of the recesses. 10

8. A shoe tree comprising a forepart composed of laterally movable sections, a pair of spaced springs seated in alined recesses in said sections acting to move said sections apart, and a plate extending between said sections and connected to one of said sections by a lost motion 15 connection for limiting the spreading movement of said sections, said plate including portions loosely enclosing the sections of said springs extending between the forepart sections and extending into the spring receiving recesses in 20 those sections thereby to prevent the turns of the springs from binding on the edges of the recesses in which they are seated and thus to allow free back and forth movement between the sections. 25
